UNITED STATES PATENT OFFICE

JAMES T. ATWOOD, OF ROCKFORD, ILLINOIS

DESIGN FOR A HINGE

Application filed November 2, 1931. Serial No. 41,596. Term of patent 14 years.

To all whom it may concern:

Be it known that I, JAMES T. ATWOOD, a citizen of the United States, residing at Rockford, in the county of Winnebago and State of Illinois, have invented a new, original, and ornamental Design for a Hinge, of which the following is a specification, reference being had to the accompanying drawing, forming part thereof.

In the drawing—

I claim:

The ornamental design for a hinge as shown.

JAMES T. ATWOOD.
